SEALING PLATE FOR SAND-FILTER CLEANERS

Filed Oct. 6, 1937

UNITED STATES PATENT OFFICE

2,141,153

SEALING PLATE FOR SAND FILTER
CLEANERSWilliam C. Laughlin, New York, N. Y., assignor
to Filtration Equipment Corporation, New
York, N. Y., a corporation of Delaware

Application October 6, 1937, Serial No. 167,625

5 Claims. (Cl. 210—128)

This invention relates to cleaning mechanisms for sand filters, and more particularly to cleaning devices for clarification filters of the type in which a relatively thin bed of sand is used as the filtering medium. The invention is particularly designed for use in conjunction with cleaning mechanisms for clarification filters of the down-flow type, although in its broader aspects it is not limited thereto.

10 In cleaning sand filters and particularly clarification filters employing a relatively thin bed of sand as the filtering material, it is now the practice to provide traveling cleaners of the type which move continuously or intermittently over the filter bed. Such cleaners are provided with agitators for creating a localized area of agitation in the sand of the filter in order to release the dirt and accumulated impurities therefrom. The dirt so released is taken up by 15 a stream of water, known as "wash water", which passes into a chamber in the cleaner from which it is preferably continuously discharged by a pump.

There are a number of known cleaning devices 20 of the above nature which are now used for clarification filters, some of which operate merely by mechanical agitation of the sand, others by the injection of jets of water into the sand, and still others by the agitation of magnetite sand or 25 other magnetic material by means of an intermittently operating electromagnet. However, all the cleaning devices of which I am aware operate upon the principle of agitating successive portions of the filter bed and withdrawing 30 accumulated impurities therefrom in the form of a water suspension, and it is an object of my invention to improve the effectiveness of any cleaner of this type by sealing off the area directly under the agitator, as will be explained. A further object resides in the provision of a sealing 35 plate adapted to travel beneath the surface of the sand of the filter directly under the area of agitation to baffle the flow of water therethrough and cause it to be dispersed laterally 40 into the sand of the filter. Other objects of the invention will be apparent from the following description when taken with the claims appended hereto.

The invention will be illustrated in greater detail by describing a preferred modification thereof as applied to the type of filter and cleaning mechanism which is described in the Laughlin et al. Patent No. 1,872,759, but it should be understood that this description is merely representative of one of a number of cleaning devices in

conjunction with which it may be used. The invention will be described with reference to the operation of a filter of the downflow type since leakage of wash water through the cleaning area is more serious in this type of filter than in one of the upflow type.

A preferred embodiment of the invention is illustrated in the accompanying drawing, in which it is shown as applied to a caisson cleaner employing an electromagnet as the agitating means, 10 and in which

Fig. 1 is a plan view of a portion of a caisson cleaner equipped with the sealing plate of the present invention, the superstructure being cut away as indicated by the line 1—1 of Fig. 2 and a 15 part of the solenoid being broken away to show the sealing plate.

Fig. 2 is a vertical section on the line 2—2 of Fig. 1, showing the cleaner as applied to a clarification sand filter of the downflow type, and 20

Fig. 3 is a longitudinal section on the line 3—3 of Fig. 1.

The caisson cleaner illustrated in the drawing is essentially the same as that described in the Laughlin et al. Patent No. 1,872,759, and 25 only so much of the structure of the cleaning mechanism is shown as cooperates with the sealing plate of the present invention. The filter illustrated is, however, a downflow filter instead of the upflow filter illustrated in this patent. 30

Referring to the drawing, the filter indicated generally by the reference numeral 1 includes a filter canal 2 of concrete or other suitable material, which may be mounted in or around the periphery of a rectangular or circular settling 35 tank or which may be entirely separate and removed some distance therefrom. A filter bed support 3 in the form of a rigid bronze grid or the like is affixed to the walls of the filter canal 2 some distance above the bottom, thereby dividing 40 the canal into an upper influent passage 4 and a lower effluent passage 5. Liquid inlets and outlets (not shown) are provided in the inlet and outlet passages 4 and 5 respectively, and the outlet passage may be provided with a control weir 45 capable of raising the level of the liquid therein above the level of the filter bed as described in greater detail in my Patent No. 1,975,109.

Supported on the grid 3 is a fine screen 6 of copper or bronze, and on this screen is a filter 50 bed 7 of sand which is preferably of 10-40 mesh in size. In the modification shown, this sand is a magnetic sand of magnetite or other material capable of being attracted by an electromagnet, although it may consist of ordinary quartz sand 55

when other types of agitators are used. The layer of said constituting the filter bed is relatively thin, in order to permit rapid filtration, and is generally of the order of 6-8 inches in thickness.

The cleaning device 10 consists generally of a caisson or cleaner tank 11, which is made up of side walls 12 and end walls 13 and which is open at its top and bottom. The rear wall 13 is preferably attached to a bottom plate 14 which extends across the full width of the caisson between the side walls 12, and the forward end thereof is preferably bent upwardly as at 15 to form a chamber 16 for the reception of wash water. Within this chamber is a pump 16a for discharging the wash water therefrom. The effective water level in the chamber 16 is determined by an adjustable weir plate 17, which is adjustably attached to the upper edge of the plate 15 as by nuts and bolts 18. A vertical baffle 19 fits across the upper part of the caisson between the side walls 12 and slightly in advance of the weir plate 17 in order to form a restricted neck or inlet 20 and to prevent the entrance of sand 25 from the filter into the chamber 16.

The caisson is provided with an agitator in the form of an electromagnet 21, in conjunction with which the sealing plate of the present invention is adapted to operate. In its most efficient form the electromagnet 21 has an open core 22, since the path of greatest magnetic permeability should extend through the material of the filter bed rather than through a soft iron core. The electromagnet or solenoid 21 is supported by cross bars 23 which are attached to angle irons 24 on top of the caisson by means of threaded rods 25 which are so adjusted that the magnet is just above the filter bed.

The cleaning mechanism which has been described is also described in greater detail and claimed in the Laughlin et al. Patent No. 1,872,759, and the above is a summary of the description given there.

In the operation of the above type of cleaner on a downflow filter, a localized area of agitation is created in the sand of the filter by the solenoid 21, or by a corresponding mechanical or hydraulic agitator. In the modification shown, the solenoid 21 is intermittently energized by a direct current, or an alternating current of relatively low frequency is passed through it. This causes the magnetite of the filter bed to be picked up, held for a fraction of a second, and then dropped back upon the screen.

In the localized area of agitation such as that existing under the electromagnet the sand of the filter offers a greatly reduced resistance to the passage of water therethrough and a stream of wash water is therefore drawn in from the effluent side of the filter. This wash water collects the dirt and impurities which have been released from the sand by reason of the agitation in the same way that the dirt is collected by the streams of water from hydraulic agitators. In both cases, the resulting suspension of dirty water is drawn in through the neck 20 and overflows the weir 17 into the chamber 16, from which it is continuously discharged by the pump 16a into an outflow channel. By proper adjustment of the weir plate 17 the current of wash water entering through the area of agitation can be so regulated as to remove substantially all the dirt from the sand and this regulation can be aided if desired by the use of a suitable control

weir in the outlet passage of the filter to adjust the effluent level of the filtered liquid.

It is apparent from the above description that the efficient operation of the cleaner results from the upward flow of currents of water through a localized area of the filter in which the sand is so agitated as to offer little resistance thereto. Experience has shown, however, that dirty wash water from the caisson will also flow through this area of agitation during the cleaner operation, and will pass downwardly through the filter and into the effluent in such large quantities as to seriously contaminate the latter. This is particularly true of cleaners equipped with very efficient agitators which churn up and wash the sand of the filter throughout its entire depth, for under these conditions there is practically no removal of dirt from the wash water during its downward passage. Comparative tests have shown that the filtered effluent may contain as much as 50 parts per million of additional solids when such a cleaner is in operation.

The present invention overcomes this source of contamination of the effluent by providing a sealing plate 30 which, in the normal operation of the cleaner tank, is embedded in the sand of the filter directly under the area of agitation and compensates for the increased permeability of the filter therein. This sealing plate 30 consists of a thin horizontal sheet of metal having sharpened edges 31 and upturned ends 32 which are attached to the side walls 12 of the caisson, as by nuts and bolts 33, directly under the agitator 21. It travels through the sand of the filter just above the screen 6 and directly under the area of agitation created by the electromagnet, and operates to baffle or deflect any direct flow of water through the area of agitation and cause it to flow laterally through the filter bed and thus follow a path through the sand thereof. This filters out the dirt and impurities contained in the wash water and prevents their admixture with the filtered effluent.

The operation of the sealing plate 30 will be illustrated with reference to the operation of the solenoid 21, in conjunction with which it is shown. When the electromagnet is energized, the magnetite sand of the filter is churned up and held for a fraction of a second, during which time the dirty water contained in the caisson has an opportunity to flow directly downwardly onto the screen 6. The plate 30 baffles this direct flow, and turns the liquid aside so that it must pass laterally through the undisturbed portion of the filter bed which holds back the impurities contained in the water.

The width of the plate 30 with respect to the agitator 21 is an important feature of the invention. It will be apparent that the plate 30, while limiting the undesired passage of dirty water downwardly through the area of agitation, can also limit to a certain extent the upward flow of wash water on which the efficient operation of an electromagnetic cleaner must depend. Accordingly, the plate 30 must not be too wide. On the other hand, too narrow a plate would not have sufficient baffling action. I have found that the most efficient sealing plate is one having an effective width which is substantially the width of the open core 22 of the solenoid 21, since this core constitutes an open channel or passage for the direct downward flow of water through the area of lessened resistance under it. Accordingly, the combination of a solenoid having an open core with a sealing plate directly

under the open core and of the same width constitutes a further specific feature of the invention.

While the invention has been described in detail in conjunction with a specific modification thereof, which accomplishes the objects of the invention in a new and improved manner, it should be understood that in its broader aspects the invention is not limited to the details shown. On the contrary, substitutions and modifications of the apparatus shown may be resorted to within the scope of the appended claims.

What I claim is:

1. A clarification filter of the downflow type comprising in combination a filter including a filter bed support, a relatively thin filter bed of sand on said support, a liquid inlet above and a liquid outlet passage below said filter bed, and a cleaning device comprising a cleaner caisson means to move the same over said filter bed, an agitator carried by said cleaner for creating a localized area of agitation in the sand of the filter, a chamber within said caisson for receiving wash water from the area of agitation, means for discharging wash water from said chamber, and a sealing plate attached to said cleaner mechanism and located immediately beneath the area of agitation and having substantially its entire bottom surface in contact with the filter bed material.
2. A clarification filter of the downflow type comprising in combination a filter including a filter bed support, a filter bed of magnetic sand on said support, a liquid inlet above and a liquid outlet passage below said filter bed, and a cleaning device comprising a movable cleaner carrying a solenoid adjacent the filter bed, said solenoid having a hollow core, and a sealing plate carrier by said cleaner directly under the hollow

of said solenoid and having substantially its entire bottom surface in contact with the filter bed material.

3. A clarification filter of the downflow type comprising in combination a filter including a filter bed support, a filter bed of magnetic sand on said support, a liquid inlet above and a liquid outlet passage below said filter bed, and a cleaning device comprising a moveable cleaner carrying a solenoid adjacent the filter bed, said solenoid having a hollow core, and a sealing plate of 10 a width substantially equal to the width of said core carried by said cleaner directly under the core and having substantially its entire bottom surface in contact with the filter bed material.

4. In combination, a filter bed, means to flow 15 influent to be filtered on top of the bed, means to remove clean effluent from beneath the bed, a movable cleaner adapted to travel over the filter bed and means to move the cleaner over the bed, said cleaner including means for creating a zone of 20 agitation in the filter bed material at a localized area whereby dirt held by the bed material is washed therefrom into the water in and around said zone, means to remove the wash water from said zone, and a plate supported by the movable 25 cleaner and movable therewith, extending substantially in a horizontal plane immediately beneath the zone of agitation and substantially at the bottom thereof to baffle the flow of dirty water through the bed at that point.

5. The combination of claim 4 in which the plate is of appreciable width in the direction of its travel and has substantially its entire lower surface in contact with the material of the filter bed.

WILLIAM C. LAUGHLIN.
